UNITED STATES PATENT OFFICE.

HORACE M. JEROME, OF DAVENPORT, IOWA, ASSIGNOR TO E. L. SCHMIDT COMPANY,
OF DAVENPORT, IOWA, A CORPORATION OF SOUTH DAKOTA.

ICE-SHAVING MACHINE.

1,426,742.

Specification of Letters Patent. Patented Aug. 22, 1922.

Application filed September 9, 1921. Serial No. 499,476.

To all whom it may concern:

Be it known that I, HORACE M. JEROME, a citizen of the United States of America, and a resident of Davenport, county of Scott, 5 and State of Iowa, have invented certain new and useful Improvements in Ice-Shaving Machines, of which the following is a full and clear specification.

The object of this invention is to provide a 10 simple, inexpensive apparatus for reducing ice to small particles by the shaving method; and the invention consists of certain novel features of construction hereinafter described and claimed.

15 In the drawing—

Fig. 1 is a side elevation of my machine; Fig. 2 is a front elevation thereof;

Fig. 3 is a vertical section of the machine; Figs. 4 to 7, inclusive, are views of details 20 hereinafter described.

Referring to the drawings annexed by reference-numerals, 10 designates a base upon which is supported a casing 11 consisting of two circular halves one of which is 25 bolted to the base and the other is secured to the former by bolts 12. Within this casing is mounted to rotate a disk 13, which is affixed to a shaft 14 journaled in bosses formed integrally with the walls of the 30 casing members and provided at one end with a hand-wheel 15 for rotating it, it being obvious, however, that a small electric motor or other power may be used instead of this hand-wheel. The disk is provided 35 with a series of radial slots or openings, and in each one of these openings is mounted a shaving-blade, every alternate blade having serrated teeth; the plane-edged blades are designated 16, while the serrated-edged 40 blades are designated 17. As shown clearly in Figs. 5, 6 and 7, the shaving-blades are formed with bevelled cutting-edges, and the serrations or teeth on the blades 17 are formed by grooving the blade transversely 45 entirely across its underside (as indicated by the closely-spaced lines in Fig. 6), said grooves cutting through the thin bevelled edges of the blades and thereby forming the teeth.

50 At the rear side of the knife-casing is arranged a hopper 18 adapted to receive the lumps of ice to be shaved. This hopper is desirably cast integral with the rear plate of the casing 11 and is located at the left of the 55 center of rotation of the knife-disk. Its bot-

tom wall 19 curves backwardly and upwardly and, together with the straight side-walls of the hopper, forms a gravity runway for the ice-lumps. The front side of the hopper opens into the casing 11 its full 60 height, so that the ice-lumps may be pressed directly against the downwardly-moving edges of the knife-blades, to thus shave off the ice and deliver it through the slots in the disk into a chute 20 cast integral with 65 the front-plate of the casing 11, this chute widening downwardly to an open lower-end, where the shaved ice will be delivered, a suitable receptacle being arranged below the top plate of the base 10 to receive the 70 shaved ice.

To press the ice-lumps against the shaving-knives and thus automatically feed the lumps to the knives, I arrange a gravity-feed device consisting of a head-plate 21 75 pivoted at 22 on the upper edges of the side-walls of the hopper 18, at a point near the casing 11. This pressure-head 21 is approximately the width of the hopper 18 and, by reason of the fact that it is pivoted near 80 the casing, at 22, it tends to normally swing toward the casing. An arm 22' is rigidly affixed adjacent to the lower edge of the pressure-plate 21 for the purpose of conveniently lifting it out of the hopper to replenish the ice-supply therein. This arm is enlarged near its lower end at 23 to form a weight which is sufficiently heavy to force the pressure-plate 21 against the ice with the desired pressure, thereby eliminating the 85 necessity of manually forcing the ice against the knives. The arm being rigidly affixed to the plate, it supports the weight clear of the bottom wall 19 and thus prevents frictional resistance. To prevent the pressure-plate 90 contacting with the knives after exhaustion of the ice, I provide the arm 22' with a stop-lug 24, which is so located as to strike against the rear edge of the hopper 18 when said pressure-plate nears the 95 knives.

It will be observed that my apparatus is simple and is capable of being inexpensively made, and, further, that the feeding of the ice to the knives is accomplished without 105 manual pressure. A further feature of importance is the alternate arrangement of serrated and plane shaving-knives, whereby the serrated edges score the ice ahead of each plane-edged knife, thereby reducing 110

the power required for cutting the ice to a minimum and making the machine very easy to run.

It will be observed further that the casing 11 covers the cutter-wheel closely on both sides except at the places where the delivery and discharge chutes are located, and both of these are positioned wholly to one side of the driving-shaft, which permits 10 the shaft to be mounted in suitable bearings formed on the outside of the inner side-wall of both the delivery and discharge chutes.

The nature and scope of the invention having been thus indicated and its preferred 15 embodiment having been specifically described, what is claimed as new is:

1. An ice-shaving machine embodying a casing formed of two sections one of which is secured to a suitable base and the other 20 being secured to and closely supported by the first-mentioned section, said first-mentioned section having a feed-hopper formed integrally therewith and said last-mentioned section having a delivery-chute formed in- 25 tegrally therewith and extending the full height of the feed-hopper, and a circular cutter-wheel mounted to rotate in said casing, said feed-hopper and delivery-chute being positioned directly opposite to each 30 other and entirely to one side of the center of rotation of the cutter-wheel, whereby both sides of the cutter-wheel are closely confined in the casing except at the points where the feed-hopper and delivery-chute 35 are positioned.

2. An ice-shaving machine embodying a

flat-faced cutter-wheel, a guard-casing surrounding said cutter-wheel and having flat inner-faces which lie closely adjacent to the flat faces of the cutter-wheel, a feed-hopper 40 and a delivery-chute forming part of the facing and being located on opposite sides thereof in alinement with each other and opening to said cutter-wheel, supporting bearings for the cutter-wheel formed on the 45 side-walls and outside of the feed-hopper and delivery-chute, and feeding means on the feed-hopper for automatically forcing the ice against the cutting-wheel.

3. An ice-shaving machine embodying a 50 flat-faced cutter-wheel provided with alternately-arranged serrated and plain-edged cutters to produce finely-shaved ice, a guard-casing surrounding said cutter-wheel and having flat inner-faces which lie closely 55 adjacent to the flat faces of the cutter-wheel, a feed-hopper and a delivery-chute forming part of the casing and located on opposite sides thereof in alinement with each other and opening to the cutter-wheel wholly to 60 one side of the axis thereof, said flat inner-faces of the casing in their close relation to the cutter-wheel forming strippers for the cutter-wheel at the edges of the casing adjacent the feed-hopper and discharge- 65 chute to prevent the finely-shaved ice passing into the body of the casing, and means in the feed-hopper for feeding the ice against the cutters.

In testimony whereof I hereunto affix my 70 signature.

HORACE M. JEROME.
